UNITED STATES PATENT OFFICE

JAMES E. GUNTER, OF BALTIMORE, MARYLAND

SLIP TOP CONTAINER AND PROCESS THEREFOR

Application filed May 16, 1927. Serial No. 191,677.

My invention relates to a new and useful slip top container and the process of closing the same, and it relates particularly to a slip top container in which the edge of the cap is curled tightly against the wall of the container after the cap is applied to the container.

The objects of my invention are to make such a closure that may be easily applied and removed, and that will hold securely after applying and that will form a reasonably tight seal after once being opened. Another object of my invention is to provide a self contained opener, which also aids in securing the tight hold the cover has upon the container, which will not be in the way of or hinder the effective use of the closing tools.

A further object is the provision of a process for the purposes stated, in which the sealing curl may be tightly curled upon a retaining and an uncurling ring, and by which, upon the uncurling of the sealing curl, the container may be opened without the necessity of the use of pressure upon, or the exposure to the operative of, sharp edges.

Other objects and advantages of the invention will be brought out more fully from the following description and the accompanying drawings which disclose several preferred embodiments thereof.

In the drawings:

Figure 1 is a front view of the top of a container showing my invention.

Figure 2 is a vertical section of the ring in the curled edge of a cap, as the cap is placed upon the container.

Figure 3 is a partial sectional view on line 3—3 of Figure 1, showing the cap tightly seamed upon the container.

Figure 4 is a partial sectional view on line 4—4 of Figure 1, also showing the cap tightly seamed upon the container.

Figure 5 shows the edge of the cap as it is uncurled upon the removal of the ring.

Figure 6 shows the invention applied to a container having nearly straight edges.

Figure 7 is a view similar to Figure 5 with a modified container shoulder and handle on the ring.

Figure 8 shows the invention applied to a bottle.

Figure 9 is a sectional view on line 9—9 of Figure 8.

Similar numerals refer to similar parts throughout the several views.

The container 1 may be made of metal, as is shown in Figures 1, 2, 3, 4, 5, and 7 or glass, as in Figures 6, 8 and 9 or any other suitable material. The cover or cap 2 is preferably 60 but not necessarily made of metal.

The container may be of any desired shape, and it may be only slightly flared at the mouth, as shown in Figure 6, or it may have an inwardly directed groove or shoulder on it, as in Figures 1 to 5 inclusive, or it may have an outwardly directed ridge, as in Figure 7, or the top of the container may be enlarged, as in Figures 8 and 9. In all these figures, except Figure 6, a definite shoulder 3 is shown, under which the curled edge 5 on the depending wall 4 on the cap is curled, or pressed.

In this curled edge a ring 6 is placed, having sufficient rigidity to partly uncurl the 75 curled edge when it is pulled out of the curled edge. This ring has a handle 7 projecting from the curled edge of the cap and the handle is thinned slightly where it projects, as shown at 8, in order not to interfere with the curling of the edge and also in order to be out of the way of the curling tools. In the modifications shown in Figures 1, 2, 3, 4 and 5 this handle is simply thinned, and when it is seamed into the curl, it may slightly break down the shoulder on the container as shown in Figures 3 and 4. When however, it is desired not to break down the shoulder, the thinned portion may be bent outwardly, to clear the shoulder, as in Figures 7, 8 and 9. 90 Or the handle may be flat against the cap wall, as in Figure 6.

The center of the cap preferably is slightly set down as shown at 9, to allow for the entrance of a chuck to hold the assembled container, cap and ring centered while completing the seam.

In Figures 3 and 7 part of the container is shown in cross-section, but above the broken line, it is shown full.

The top edge of the container may be curled or beaded as at 10 in Figure 2.

A gasket may be used, as at 11, in Figures 3, 6 and 9.

5 The container is preferably assembled as shown in Figure 2, and upon the lower edge of the cap being curled in further, and pressed tightly upon or against the container wall, it hugs the container wall tightly, whether 10 there be a shoulder on the wall or not, and it is quite difficult to remove the cap. When 15 it is desired to remove the cap, the handle of the ring is grasped, and preferably pulled upwardly and outwardly, away from the axis of the container, and thereby the curled edge 20 of the cap is uncurled, and the cap wall is pulled away from the container wall, as shown in Figure 5. The cap may then be readily pushed up with one's thumbs without cutting them and without danger of spilling the contents. The cap may be replaced on the container to keep the contents of the container, and a nearly air tight seal is obtained. Upon 25 once opening the container, it cannot be closed without detecting that opening.

This cap may be applied at the can factory and then the other end would be sealed on by the packer, at his factory.

As many changes might be made in the 30 above arrangements and as many variations may be made without departing from the scope of the invention, it is intended that all features herein described or shown in the accompanying drawings shall be interpreted as 35 illustrative, and that the invention be limited only by the following claims.

I claim:

1. The process of closing a container which consists in positioning upon an open end of 40 a container a cap having a wall with an outwardly curled lower edge, providing a removable member in said curled edge, removably securing said cap in clamping position by further curling said edge tightly 45 around said removable member and inwardly and tightly against said container.

2. The process of closing a container which consists in positioning upon an open end of a container a cap having a wall with an outwardly curled lower edge, providing a removable member in said curled edge with a projecting handle, removably securing said cap in clamping position by further curling said edge tightly around said removable member and inwardly and tightly against said container.

3. The process of closing a container which consists in positioning upon an open end of a container a cap having a wall with an outwardly curled lower edge, providing in said curled edge a removable member with a handle projecting from between said curled edge and cap wall, and being thinned where it projects, removably securing said cap in clamping position by further curling said edge tightly

around said removable member and inwardly and tightly against said container.

4. In combination, a container, a cap thereon having a depending wall with an outwardly curled lower edge surrounding one end of the container, said curled edge being adapted to be forced inwardly and tightly against the container wall, and means to positively uncurl said curl, and thereby to loosen said cap upon the container. 70 75

5. In combination, a container, a cap thereon having a depending wall with an outwardly curled lower edge surrounding one end of the container, said curled edge being adapted to be forced inwardly and tightly against the container wall and means in said curled edge to positively uncurl the same. 80

6. In combination, a container, a cap thereon having a depending wall with an outwardly curled continuous lower edge surrounding one end of the container, said curled edge being adapted to be forced inwardly and tightly against the container wall and a ring in said curl with a projecting handle. 85

7. In combination, a container, a cap thereon having a depending wall with an outwardly curled continuous lower edge surrounding one end of the container, said curled edge being adapted to be forced inwardly and tightly against the container wall and a ring in said curl with a projecting handle, said projecting handle being thinned where it projects from said curl. 90 95

8. In combination, a container, a cap thereon having a depending wall with an outwardly curled lower edge surrounding one end of the container, a removable ring in said curl with a projecting handle whereby to remove said ring said curled edge being adapted to be curled tightly upon said ring and at the same time to be forced inwardly and tightly against the container wall. 100 105

9. In combination, a container, a cap thereon having a depending wall with an outwardly curled lower edge, a ring in said curled edge, said curled edge and ring tightly surrounding said container and thereby holding said cap upon the container, said ring being adapted to be removed from said curled edge and thereby to partially positively uncurl said curled edge. 110 115

10. In combination, a container, a cap thereon having a depending wall with an outwardly curled lower edge, a ring in said curled edge having a handle projecting from said curled edge, said curled edge and ring tightly surrounding said container and thereby holding said cap upon the container, said ring being adapted to be removed from said curled edge and thereby to partially positively uncurl said curled edge. 120 125

11. In combination, a container, a cap thereon having a depending wall with a continuous outwardly curled lower edge, a ring in said curled edge having a handle project- 130

ing from the curled edge, said handle having a thinned section where it projects, whereby the curling of said edge is not obstructed by said handle, said curled edge and ring tightly surrounding said container and thereby holding said cap upon the container, said ring being adapted to be removed from said curled edge and thereby to partially uncurl said curled edge.

12. In combination, a container, a cap thereon having a depending wall with an outwardly curled lower edge surrounding one end of the container, a ring in said curled edge, said curled edge being adapted to be curled tightly upon said ring and inwardly and tightly against the container wall, said ring being adapted to be removed from said curled edge and upon its removal to partially positively uncurl the same.

13. A slip cap container comprising a container and a removable and replaceable cap, the lower edge of said cap being turned outwardly, upwardly and then inwardly to form a bead compressed against the wall of the container and means to pry open said bead and thereby to decrease the hold thereof on the container wall.

14. The combination with a container of a cap having an outward inwardly facing wall parallel to and engaging the outer wall of a container, the lower edge of the cap wall having an outward upwardly opening bead thereon compressed inwardly against the container wall, and means to partially open said bead to decrease the hold thereof on said container wall.

15. A container seam comprising a container wall and a removable and replaceable cap, characterized by the cap having an outer downturned wall the lower edge thereof curled into an outwardly and upwardly directed bead compressed against the wall of the container and means to partially open said bead to decrease the hold thereof on the container wall.

JAMES E. GUNTER.
